CLAIM

The ornamental design for artificial lash extensions, as shown and described.

DESCRIPTION

FIG. 1 is a top left perspective view of an artificial lash extension for the natural eyelashes of a first eye, in accordance with the claimed design.

FIG. 2 is a top view thereof.

FIG. 3 is a bottom view thereof.

FIG. 4 is a left side view thereof.

FIG. 5 is a right side view thereof.

FIG. 6 is a rear view thereof.

FIG. 7 is a front view thereof.

FIG. 8 is a top left perspective view of an artificial lash extension for the natural eyelashes of a first eye in accordance with the claimed design, wherein the break lines indicate indeterminate length.

FIG. 9 is a top view of thereof, wherein the break lines indicate indeterminate length.

FIG. 10 is a bottom view thereof, wherein the break lines indicate indeterminate length.

FIG. 11 is a left side view thereof, wherein the break lines indicate indeterminate length.

FIG. 12 is a right side view thereof, wherein the break lines indicate indeterminate length.

FIG. 13 is a rear view thereof, wherein the break lines indicate indeterminate length.

FIG. 14 is a front view thereof, wherein the break lines indicate indeterminate length.

FIG. 15 is a top left perspective view of an artificial lash extension for the natural eyelashes of a first eye in accordance with the claimed design, wherein the break lines indicate indeterminate length.

FIG. 16 is a top view of thereof, wherein the break lines indicate indeterminate length.

FIG. 17 is a bottom view thereof, wherein the break lines indicate indeterminate length.

FIG. 18 is a left side view thereof, wherein the break lines indicate indeterminate length.

FIG. 19 is a right side view thereof, wherein the break lines indicate indeterminate length.

FIG. 20 is a rear view thereof, wherein the break lines indicate indeterminate length.

FIG. 21 is a front view thereof, wherein the break lines indicate indeterminate length.

FIG. 22 is a top right perspective view of an artificial lash extension for the natural eyelashes of a second eye opposite the first eye, in accordance with the claimed design.

FIG. 23 is a top view thereof.

FIG. 24 is a bottom view thereof.

FIG. 25 is a left side view thereof.

FIG. 26 is a right side view thereof.

FIG. 27 is a rear view thereof.

FIG. 28 is a front view thereof.

FIG. 29 is a top right perspective view of an artificial lash extension for the natural eyelashes of a second eye opposite the first eye in accordance with the claimed design, wherein the break lines indicate indeterminate length.

FIG. 30 is a top view of thereof, wherein the break lines indicate indeterminate length.

FIG. 31 is a bottom view thereof, wherein the break lines indicate indeterminate length.

FIG. 32 is a left side view thereof, wherein the break lines indicate indeterminate length.

FIG. 33 is a right side view thereof, wherein the break lines indicate indeterminate length.

FIG. 34 is a rear view thereof, wherein the break lines indicate indeterminate length.

FIG. 35 is a front view thereof, wherein the break lines indicate indeterminate length.

FIG. 36 is a top right perspective view of an artificial lash extension for the natural eyelashes of a second eye opposite the first eye in accordance with the claimed design, wherein the break lines indicate indeterminate length.

FIG. 37 is a top view of thereof, wherein the break lines indicate indeterminate length.

FIG. 38 is a bottom view thereof, wherein the break lines indicate indeterminate length.

FIG. 39 is a left side view thereof, wherein the break lines indicate indeterminate length.

FIG. 40 is a right side view thereof, wherein the break lines indicate indeterminate length.

FIG. 41 is a rear view thereof, wherein the break lines indicate indeterminate length; and,

FIG. 42 is a front view thereof, wherein the break lines indicate indeterminate length.

The broken lines consisting of evenly spaced lines in the figures show portions of the artificial lash extension that form no part of the claimed design. The break lines consisting of dashed dot lines that separate parts of the artificial lash extension represent indeterminate length and form no part of the claimed design.
